UNITED STATES PATENT OFFICE

144,275

DESIGN FOR A COMBINED TOOTHBRUSH, DENTIFRICE CONTAINER, AND BRUSH SHEATH

Anna E. Vandeventer, Riverside, Calif.

Application September 28, 1945, Serial No. 122,392

Term of patent 14 years

(Cl. D9—2)

To all whom it may concern:

Be it known that I, Anna E. Vandeventer, a citizen of the United States, residing at Riverside, in the county of Riverside and State of California, have invented a new, original, and ornamental Design for a Combined Toothbrush, Dentifrice Container, and Brush Sheath, of which the following is a specification, reference being had to the accompanying drawing, forming part thereof.

Fig. 1 is a perspective view in open position of a combined toothbrush, dentifrice container, and brush sheath embodying my new design, and

Fig. 2 is a side elevational view thereof in closed position.

I claim:

The ornamental design for a combined toothbrush, dentifrice container, and brush sheath substantially as shown.

ANNA E. VANDEVENTER.
